UNITED STATES PATENT OFFICE.

JAMES K. BURLEIGH, OF KALAMAZOO, MICHIGAN, ASSIGNOR TO AMERICAN SIGN COMPANY, OF KALAMAZOO, MICHIGAN.

SIGN.

1,045,942.

Specification of Letters Patent.

Patented Dec. 3, 1912.

Application filed May 21, 1912. Serial No. 698,712.

To all whom it may concern:

Be it known that I, JAMES K. BURLEIGH, a citizen of the United States, residing at Kalamazoo, Michigan, have invented certain new and useful Improvements in Signs, of which the following is a specification.

This invention relates to improvements in signs.

The main objects of this invention are to provide in a sign in which the sign indicia or characters are formed of lenses illuminated by lamps, an improved lens by which "spot" lights are effectively obviated. Further, to provide an improved means for securing the lenses of such structures in which the parts are economically produced and easily and quickly assembled.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Fig. I is a detail front view of a sign structure embodying the features of my invention, a single letter only being illustrated, the parts being shown mainly in conventional form. Fig. II is a detail section taken on a line corresponding to line 2-2 of Fig. I, through the face plate, the lens being shown in full lines. Fig. III is a detail inside view of the face plate and one of the lenses. Fig. IV is a detail perspective view of the face plate showing one of the lens openings and securing lug 11. Fig. V is a sectional detail through the casing walls showing one lens and a lamp. Fig. VI is a side elevation of a modified form of lens, in which the shank of the lens is provided with a complete screw thread instead of the rib shown in Fig. II.

In the drawings, similar reference characters refer to similar parts throughout the several views, and the sectional views are taken looking in the direction of the little arrows at the ends of the section lines.

Referring to the drawing, 1 is a sheet metal face plate of a sign. The face plate is, in practice, the wall of a casing, in which

the illuminating lamps, as 2, are inclosed. As the structural details of the casing form no part of my present invention, I do not illustrate or describe the same herein. A satisfactory casing structure is shown in the 60 patent to Smith, No. 962,724, dated July 28th, 1910, and I preferably embody my improvements in a sign of the character there indicated.

The lenses 3 are arranged in the face plate 65 in groups to form the sign indica or characters, or to produce any suitable design or outline. The lenses 3 are preferably convex and provided with cylindrical shanks 4, the inner sides of the lenses being flat to provide 70 shoulders 5. The ends of the shanks are pyramidal to provide a plurality of refracting surfaces 6. The face plate is provided with circular openings 7, of such diameter that the shanks are a turning fit therein. 75 The shanks are provided with thread-like ribs 8, which are spaced from and are substantially parallel with the shoulders 5. The ends of the ribs are spaced at 9, and one end deflected toward the end of the shank, 80 as at 10.

The lug 11, which is formed of a piece of sheet metal folded over the edge of the opening, as shown, engages the rib 8 to retain the lens in place, the lens being turned to 85 bring the lug between the rib and the shoulder. This forms a simple and effective securing means for the lens, and one which enables the lenses to be assembled very rapidly.

In the modified structure shown in Fig. 6, the shank is provided with a complete screw thread 12, the inner end of the thread being spaced from the shoulder to receive the lug. By forming the shanks of the 95 lenses as described,—that is, with their ends pyramidal, a plurality of refracting faces is provided, so that the lenses in different positions in the casing relative to the lamps contained therein transmit substantially 100 uniform amounts of light. A further advantage is that "spot" lights are obviated. For instance, if a lens is placed substantially in front of a lamp, as is shown in Fig. V, the refracting surfaces on the lens 105 shank prevent the light shining directly through the lens, as is the case with lenses of the type now commonly used; that is, lenses having concave shanks. This obviates the necessity for the use of shields, 110

and the necessity of great care in the placing of the lamps relative to the lenses, and further, the lenses transmit a uniform amount of light, thus greatly adding to the appearance of the sign. Owing to the pyramidal form of the shank, care of the adjustment of the lens in the openings is not required, as there is no necessity for adjusting the lenses to bring the refracting surfaces into position relative to the lamp.

Having thus described my invention, what I claim as new and desire to secure by Letters Patent is:

1. A sign comprising a face plate of sheet metal containing a substantially circular opening, a clip-like lug folded over the edge of the opening, and a lens provided with a shoulder arranged to contact with the side of the plate and with a shank having a thread-like lug engaging rib spaced from and parallel with the shoulder, there being a space between the ends of the rib adapted to receive said lug, one end of the rib being curved toward the end of the shank.

2. A sign comprising a face plate of sheet metal containing a substantially circular opening and provided with a lug projecting into the circle of said opening, and a lens provided with a shoulder arranged to

contact with the side of the plate and with a shank having a thread-like rib spaced from and parallel with said shoulder, there being a space between the ends of the rib adapted to receive said lug, one end of the rib being deflected toward the end of the shank.

3. A sign comprising a face plate of sheet metal containing a substantially circular opening; a clip like lug folded from the edge of the opening; and a lens provided with a shoulder arranged to contact with the side of the plate and with a shank having a thread-like lug-engaging rib.

4. A sign comprising a face plate of sheet metal containing a substantially circular opening and provided with a single lug projecting from the edge of the opening in the plane of the face plate, and a lens provided with a shoulder arranged to contact with the side of the plate and with a shank having a thread-like lug engaging rib.

In witness whereof, I have hereunto set my hand and seal in the presence of two witnesses.

JAMES K. BURLEIGH. [L. S.]
